Application July 15, 1952, Serial No. 298,941

Claims priority, application Netherlands July 28, 1951

2 Claims. (Cl. 315—21)

This invention relates to devices utilizing a cathode-ray tube and to a cathode-ray tube suitable for use in such devices.

The main object of the invention is to provide a cathode-ray tube comprising an electron gun for producing an electron beam with means for converging the beam to strike particular points on a target.

This and other objects of the invention will be best understood from the following description.

According to the invention, a cathode-ray tube comprising an electron gun, including a cathode and an accelerating anode, and a collecting electrode or target is provided with a pair of special coating spaced grids mounted between the accelerating anode and the target for focussing an electron beam produced by the electron gun and travelling in substantially parallel lines toward the target. The solid portions of the second grid, i. e. the grid furthest from the source of the electron beam, are arranged behind the centers of the apertures formed by the solid portions of the first grid. The grids, accelerating anode and target are spaced apart distances and are maintained at potentials at which the electron beam formed by the electron gun is concentrated into at least one ray in the direction of the target. The potentials applied to the various electrodes are preferably chosen so that, with a given potential applied to the cathode, the potentials on the grids are greater than that on the cathode and so that the potential on the target is not less than the potential on the grid having the lower potential. By superimposing an alternating current voltage on the potential applied to at least one of the grids, a displacement of the point of impact of the electrons on the target may be obtained.

This arrangement in which displacement of the points of impact or focal point of the electron beam is obtained may be utilized in many ways to materially increase the number of control possibilities for an electron beam and, consequently, to expand considerably the field of application of cathode-ray tubes. So, for example, cathode-ray tubes may now be utilized for the amplification of oscillations, for frequency multiplication, for producing oscillations, for switching arrangements and so forth.

The invention will now be described with reference to the accompanying drawing in which:

Figs. 1 to 4 are simplified diagrammatic views serving to illustrate the principle underlying the invention;

Fig. 5 is a view, in cross-sections, of one form of cathode-ray tube according to the invention, together with a portion of the associated circuit arrangement.

Referring to Fig. 1, a pair of spaced grids 2, 3, having parallel wires at right angles to the plane of the drawing, are located in front of a collecting electrode or target 1. The wires of the second grid 3 are arranged behind the centers of the apertures formed by the wires of the first grid. An electron beam travelling toward the target along substantially parallel paths, shown by parallel lines, intercepts the two grids 2, 3.

The beam is divided by the two grids into a number of

2

small beams equal to the number of half the meshes of that part of the first grid through which the electron beam passes since the small beams are produced between a wire of the first grid and a wire of the second grid.

In order to obtain convergency of the small beams, potentials are applied to the grids at which the voltage on the grid having the lower voltage should be, at the most, equal to the voltage on the collecting electrode and the two grids should have a voltage exceeding the cathode voltage. However, the fulfilment of these requirements does not guarantee that converging beams are obtained since, for this purpose, the value of f in the following equation must exceed zero.

$$\frac{1}{f} = \frac{1}{f_1} + \frac{1}{f_2} \quad (1)$$

In this Equation 1

$$f_1 = \frac{kV_{g^1}}{V_{g^2} - V_{g^1} - V_{s^1} - V_k} \quad (2)$$

and

$$f_2 = \frac{kV_{g^2}}{V_s - V_{g^2} - V_{g^1} - V_k} \quad (3)$$

where:

V_k is the voltage at the electrode immediately preceding the first grid;

V_{g^1} is the voltage at the first grid;

V_{g^2} is the voltage at the second grid;

V_s is the voltage at the collecting electrode;

l_1 is the spacing between the electrode preceding the first grid and the first grid;

l_2 is the spacing between the first grid and the second grid;

l_3 is the spacing between the second grid and the collecting electrode;

k is a constant, the value of which lies between about 2 and 4;

f_1 is the focal distance of the lenses formed by the first grid; and

f_2 is the focal distance of the lenses formed by the second grid.

From the equations indicated above (1), (2) and (3), the focal distance of the beams varies with the voltages at the grids, at the collecting electrode and at the electrode immediately preceding the first grid; the absolute voltages are, however, as with any electron-optical system, not the measure but the ratios between the voltage. Therefore, in order to simplify the explanation of the operation of a device according to the invention, it is assumed in the following description that the voltages at the collecting electrode and the electrode immediately preceding the first grid (in general the accelerating anode) are constant and that only the grid voltages are varied.

If the grid voltages are varied (within the requirements mentioned above), there occurs not only a variation of the focal distance, but also a displacement of the

focal points in a manner such that the focal points of two beams located on different sides of a wire of the second grid move in opposite senses. This displacement v may be represented, if the voltages V_{g^1} and V_{g^2} do not vary too greatly, by the following equation:

$$v = d_4 \left(\frac{l_2 + l_3}{f_1} - \frac{l_3}{f_2} \right) \quad (4)$$

where d = the spacing between two solid adjacent parts, for example, two adjacent wires of a grid.

The focal points or lines may, of course, be located in front of, on or behind the collecting electrode. For the sake of simplification it will hereinafter be assumed

that the focal points or lines are on the collecting electrode. If the grid voltages have been adjusted in this manner, an alternating voltage superimposed on one or on both grid voltages will, in general, produce a variation both of the focal distance and of the position of the focal point. It can be shown from the equations indicated above (1), (2), (3) and (4), that by supplying the alternating voltage in phase opposition to the two grids, high control-voltages are permissible so that great displacements of the focal points may be obtained without appreciable variation in focal distance. However, the formulas, equations and results mentioned above are to be regarded only as approximations. The only requirement is that the grids should produce convergent beams.

From the above description and from the equations, it is evident that the spacing between the grids and that between the grids and the collecting electrode and the electrode preceding the first grid affect both the focal distance and the displacement of the focal points. In general, the spacing between the electrode preceding the first grid and the collecting electrode will be large with respect to the spacing between the grids; it is preferably chosen to be more than five times the latter spacing.

Referring to Fig. 1, direct voltages exceeding the cathode voltage are supplied to the grids 2 and 3. The concentration of the beam due to these voltages, as illustrated in Fig. 1, is obtained when $f_1/f_2 = 1 + l_2/l_3$. The displacement v , represented by Equation 4, is then zero. By supplying an alternating control-voltage to one grid or to both grids 2 and 3, the focal points on the collecting electrode 1 may be displaced. Fig. 2 illustrates a condition in which the focal points are displaced without substantial variation of the focal distance. This may be obtained by supplying the control-voltage in phase opposition to the grids 2 and 3. This control-method is assumed to be carried out in the cases shown in Figs. 3 and 4 also.

The condition illustrated in Fig. 2 is a particular one in that the displacement of the focal points is such that always two focal points of the beams shown in Fig. 1 coincide behind a wire of the grid 3. Consequently, the current strength at the point of impact on the collecting electrode will be twice that at the point of impact on the collecting electrode with the distribution on the focal points shown in Fig. 1.

Fig. 3 illustrates another particular condition in which two beams coincide in a focal point now located behind a wire of the grid 2. The control-voltage may also be raised to such a value that the beams cross one another. Such a condition is illustrated in Fig. 4.

Fig. 5 shows one form of cathode-ray tube exemplifying the invention in which the collecting electrode is subdivided. In this figure, a discharge tube 4 comprises a collecting electrode 5 subdivided into a number of electrodes connected alternatively to one another and to the primary winding of an output transformer 6. The tube 4 furthermore comprises a cathode 7, which can be heated by a filament wire 8, and an accelerating anode 9 for concentrating the electrons emitted by the cathode 7 into a single beam in which the electrons follow substantially parallel paths. This beam is converged by a pair of grids 10 and 11 and directed either to one or to the other series of collecting electrodes by an alternating control-voltage supplied through a transformer 12. Reference numeral 13 designates a source of voltage across which is connected a potentiometer 14 from which the voltages for the various electrodes are taken. With the tube shown in Fig. 5, the collecting electrodes are constituted by strips at right angles to the plane of the drawing and the grids 10 and 11 comprise solely parallel wires parallel to these strips. Consequently, the beams produced by the grids 10 and 11 have a dimension at right angles to the plane of the drawing considerably exceeding the dimension in the plane of the drawing at right angles

to the grid wires. The cathode 7 and the accelerating anode 9 are constructed such that a beam is produced which bombards the whole surface of the grid with electrons travelling along paths which are substantially parallel to one another. The device shown in Fig. 5 may be used to produce oscillations by providing a coupling between the output electrodes and one grid or both grids.

It should be noted that instead of using an electron beam, the dimensions of the cross sectional area of which substantially correspond to the dimensions of the grids, use may, as an alternative, be made of an electron beam having a small cross sectional area; in this case the beam may be deflected prior to passing through the grid 10 in a conventional manner such that it completely scans 15 the surface of the grid parallel to the direction of the wires or at an angle thereto.

In Figure 5, the grids comprise solely parallel lines. In such as case, the constant k in the Equations 1, 2, and 3 is usually chosen to be about 2. A simple combination of parallel wire grids is where the first grid comprises three parallel wires and the second grid comprises two parallel wires parallel to the wires of the first grid and located centrally behind the apertures between the wires of the first grid. The grids, however, may also be constituted by a perforated plate and, in this case, k is chosen to be about 4. As a further alternative, the grids may also comprise crossed wires. The intensity of the electron beam may be varied by means of a diaphragm or a so-called Wehnelt cylinder.

For certain purposes, the collecting electrode or target may be constituted by a luminescent screen on which a line or dot frame may be described. Since convergency of the beam requires an electrostatic field between the grids and the target, a conductive member, such as a grid, 35 must be provided in front of or behind the screen which, however, does not prevent the beam from striking the screen. The charge produced on the screen by the electron bombardment may be avoided by conventional means, for example, sufficient secondary emission of the screen.

As an alternative for the conductive member, the luminescent screen may be provided with a conductive substance, for example, metal. As a further alternative, the side of the screen facing the electron gun may be provided with a metal coating pervious to electrons.

While we have thus described our invention with specific examples and embodiments thereof, other modifications will be readily apparent to those skilled in the art without departing from the spirit and the scope of the invention as defined in the appended claims.

What we claim is:

1. An electron discharge device comprising an electron gun including a cathode and accelerating anode for producing an electron beam, a collecting electrode, a pair of adjacent grids mounted between said collecting electrode and said accelerating anode and closer to the collecting electrode, each of said grids being constituted solely of a plurality of parallel fine wires lying in a single plane, the plane of the wires of one of said grids being spaced from and therefore different than the plane of the wires of the other grid, the wires of the grid adjacent the collecting electrode being parallel to the wires of the other grid and being located centrally behind the apertures defined by adjacent wires of said other grid, a source of D.-C. potential, means for applying a given potential to said cathode, means for applying potentials exceeding said given potential to said grid and accelerating anode, means for applying a potential to said collecting electrode which is not less than the potentials applied to said grids, said grids, accelerating anode and collecting electrode being spaced apart distances at which with the potentials applied thereto the beam is caused to converge towards the collecting electrode, a source of A.-C. control potentials, and means for applying A.-C. control potentials from said source to said pair of grids in different planes for deflecting the beam in accordance with

said control potentials and to cause the beam to impact different portions of the collecting electrode.

2. An electron discharged device as set forth in claim 1 wherein the spacing between the two grids is small relative to the spacing between the accelerating anode and collecting electrode, the collecting electrode is constituted by a plurality of alternately-connected strip-like members extending parallel to the grid wires, and the A-C. control potentials are applied across the two grids in phase opposition.
